UNITED STATES PATENT OFFICE.

CHARLES S. LANMAN AND WILLIAM N. ESCHLEMAN, OF COLUMBUS, OHIO; ELLEN
ESCHLEMAN ADMINISTRATRIX OF SAID WILLIAM N. ESCHLEMAN, DECEASED.

MACHINE FOR MANUFACTURING NUTS.

1,185,805.

Specification of Letters Patent.

Patented June 6, 1916.

Application filed March 25, 1912. Serial No. 686,148.

To all whom it may concern:

Be it known that we, CHARLES S. LANMAN and WILLIAM N. ESCHLEMAN, citizens of the United States, residing at Columbus, in the county of Franklin and State of Ohio, have invented certain new and useful Improvements in Machines for Manufacturing Nuts, of which the following is a specification.

10 Our invention relates to a machine for manufacturing nuts and is particularly designed to provide a machine for forming nuts, especially nuts of a hexagonal type, in a manner calculated to produce the least 15 possible distortion of the nut blank in the forming, while at the same time saving a comparatively large percentage of the "scrap" which has hitherto been impractical, although attempted in various ways.

20 Our invention therefore resides in the provision of a machine for forming nut blanks by a swaging forming action and renders such swaging forming action feasible without crowding the material in the nut blank 25 or bulk material by the provision of means rendering possible the definite calculation of the amount of stress exerted in forming the nut blank so that it will not be crowded and at the same time positively restraining both 30 the nut blank and the bulk material from any tilting or twisting action.

In the concrete form of our invention as embodied in the drawing forming a part 35 of this application, we utilize forming cutters which approach each other in their operation upon the work in convergent paths of travel away from the nut blank. In this convergent approach they tend, if anything, to withdraw the nut blank from the permanent gage desirably utilized in connection 40 therewith and are, in fact, so directed and formed as to effect the forming action of adjacent sides of the nut blank against a restraint of the nut blank, which is due only to the material connecting the nut blank to the bulk 45 material. This cutting forming action is accurately calculated and timed so as to sever and form the nut blank without crowding it against its immovable gage and so as 50 to leave such nut blank in position to rest against such gage at the end of the cutting action. It is just as essential, however, that this convergent cutting and forming action of the tools with the result stated, be 55 furthered and assisted by a restraint of the

nut blank and bulk material against any movement other than may be necessary to prevent crowding.

Therefore, by way of specific reiteration, the machine shown in the accompanying 60 drawings for effecting the formation of nuts in the manner described by us, comprises angularly approaching cutters, whose points are at all times in alinement and which serve to carry the nut blank away from a positive gage just sufficient to prevent crowding and no more. In addition, there are provided means for clamping both the bulk material and the nut blank during the cutting operation, so as to prevent tilting or twisting 65 of either article and to thereby obviate irregularities of formation. Our invention is particularly applicable to the formation of hot pressed nut blanks, but may be suitable for the formation of nut blanks of a 70 different nature.

Various other important features of our invention will be developed in the course of the succeeding specification and description of the preferred embodiment of our invention 80 which is shown in the accompanying drawings.

In the form shown in the accompanying drawings, similar characters of reference designate corresponding parts and, therein: 85

Figure 1 is a top plan view of a machine for forming nut blanks having our improvement embodied therein, Fig. 2 is a longitudinal section of our machine showing the bed and piercing structure of the machine in elevation and the cutter structure in section and detail, Fig. 3 is an enlarged view of the cutter structure shown in Fig. 1, Fig. 4 is an elevation of the cutter structure shown in Fig. 2, Fig. 5 is a face view 90 of the cutter structure in substantially complete form and shown removed from the base, Fig. 6 is a detail of one form of blank retaining means which may be used in our machine, Fig. 7 is a modified form of this 95 blank retaining means, Fig. 8 is a side elevation of either form of blank retaining means shown in Figs. 6 and 7, Fig. 9 is a face view on a reduced scale of our housing for the cutter members, Fig. 10 is a detail 100 view on a reduced scale of the yoke member which carries the lower cutting tool and which is to be operatively mounted in the housing shown in Fig. 9, Fig. 11 is a detail 105 on a reduced scale of the upper tool carry- 110

ing member which is operable within the yoke shown in Fig. 10, Fig. 12 is a sectional view taken on line 12—12 of Fig. 3, and, Fig. 13 is a sectional view taken on line 5 13—13 of Fig. 3. Figs. 14 to 18 illustrate in progressive stages the various positions of the cutter elements with respect to the stock bar and gage in forming a complete blank.

10 In the drawings, the framework of our machine is shown at 1 and mounted therein is a driving shaft 2 supported partially by a bearing 3 and carrying pulleys 4 and a fly wheel 5. The inner end of this shaft 15 carries a pinion 6 which meshes with gears 6^a and 8. The gear 6^a meshes with gear 7 and gear 8 meshes with a third gear 9 upon a cam shaft 10 having a series of cam elements thereon which are designed to control 20 and operate the essential parts of our machine in a manner to be hereinafter described.

In connection with the essential parts of our mechanism for initially forming nut 25 blanks of hexagonal form, we shall omit all reference to the structure of those elements which are known as the piercing elements and which are designed to complete the formation of the nut blank by a piercing there- 30 of, in a manner well understood. In the showing in the drawings, however, it is necessary to show a small portion of this piercing mechanism as, for instance, such as shown in Fig. 2, where the nut blank is 35 shown clamped between two forming tools B within which the piercer rods operate in the manner described in our companion application, Serial Number 692,453, filed April 22, 1912.

40 Referring to Fig. 5, wherein the framework of the machine is designated generally as 1, it will be seen that there is a guide shelf 11 upon which the heated bar is designed to rest and be supported during the 45 successive forcing of the same forwardly by the operator and this bar is limited in its inward movement by the provision of a stationary gage element 12 which may vary in form in adaptation to our invention. These 50 variations of form will be referred to later in the specification, it being only necessary to understand that the heated bar is supported in some manner during the severance of the blank therefrom by the shelf 11 55 and other suitable means for preventing twisting or wabbling.

Special reference will be had in the following paragraph to the structure shown in detail in Figs. 9, 10 and 11 and in assembled 60 form in Figs. 5, 12 and 13.

The swaging elements used in our invention are shown at 13 and 14 and the element 13 is adjustably mounted by means of the adjusting bolt 15 in the pocket 16 of the 65 member 17 (shown in Fig. 11), such mem-

ber 17 having a cam receiving pocket 18 and integral slide block formations 19 and 20 which fit within a channel-way of an element to be shortly described. The pocket 16 (shown best in Fig. 13) is provided with 70 a tapered longitudinal side 21 and bearing thereagainst and against the swaging element 13 is a wedge fastening block 22 held in place by bolts 23 and designed to force the swaging element 13 against the opposite 75 longitudinal wall of the pocket 16. This serves to steady the tool against lateral stresses. This tool carrying member 17 is slidably mounted within a yoke 24 (shown in Fig. 10) which is provided at its base 80 with a tool receiving pocket 25 of similar form to the pocket 16 and having the tool 14 mounted therein and adjustable by means of the bolt 26. The tool is braced against lateral stress by a wedge element 27 having 85 securing bolts 28 and operating against an inclined side wall 29. The member 24 is further provided with a cut-away portion 90 30 and with multiple cam receiving pockets 31 and 32 on either side of a cut-away portion 33 within which fits the cam pocket forming structure 18 of the member 17. It will be understood at this point that the member 17 fits within the yoke member 24 95 with the pocket forming member 18 extending into the space 33. The pocket structure 16 in the member 17 carries what may be termed the upper tool, while the pocket structure 25 in the member 24 carries the lower tool and these tools are adapted to 100 move toward each other in their operation of swaging the blank from the bar. Referring to Fig. 5 and remembering that the member 17 is slidably mounted within the yoke member 24, it will be apparent that the 105 member 17 which is the inner member, has its cam receiving pocket 18 in embracing relation to a cam 34 upon the cam shaft 10, while the cam receiving pockets 31 and 32 of the yoke member 24 respectively embrace 110 cams 35 and 36. These cams are of considerable width, for a purpose to be shortly described and are also designed to force the inner member 17 downwardly synchronously with the upward lifting of the outer 115 yoke member 24 and likewise to synchronously move the said members in opposite directions. It will thus be seen that the tools are positively brought together by the relative reciprocation of their supporting 120 members and are likewise moved apart by such relative reciprocation. So far, we have described the tools as moving in a direction perpendicular to the bar of metal being operated upon. The swaging tools are caused 125 to move at an angle to this perpendicular path of travel as is illustrated by the arrow in Fig. 17 by the provision of an inclined rib 37 upon the rear of the supporting member 24, such inclined rib being effective by 130

coöperation with the structure of supporting plate shown in Fig. 9 and designated 38. This supporting plate is in reality a part of the framework designated generally as 1 5 and comprises bearings 39 and 40 with an intermediate concave portion 41. The plate further preferably has a die housing of suitable form as at 42; but the essential portion of the plate is an inclined groove 10 43—44 having one wall formed by adjustable wedge elements 45 and 46. This groove 43—44 is designed to receive and form a guideway for the rib 37, it being very feasible to regulate the closeness of the fit of the 15 said rib within the groove 43—44 by regulation of the position of the wedge members 45—46. It will be understood from this that, while the members 17 and 24 reciprocate relatively, the member 24 at the same 20 time reciprocates with relation to the supporting plate 38 and the fitting of the rib 37 within the groove 43—44 causes the supporting member 24 to move upwardly and downwardly at an angle. The movement of 25 the member 24 upwardly and downwardly at an angle, necessarily carries the member 17 with it; and it must be kept in mind that during this movement at an angle of both the supporting members 17 and 14 carrying 30 their tools, such tools are relatively reciprocated by the action of the cam thereon and such relative reciprocation maintains the points of such tools in vertical alinement at all times as is shown diagrammatically in 35 Figs. 14 to 18 inclusive. The angular movement of the supporting members 17 and 24 is rendered possible by the unusual width of the cams, as mentioned in the last paragraph.

40 The operation as thus far described, will plainly insure a biting of the swaging elements into the bar and a continued movement therethrough at an angle to produce a shearing cut, while at the same time maintaining the opposing points of the tool in vertical alinement and swaging a comparatively small portion of the excess material into the nut blank as will appear particularly from an inspection of Figs. 16 and 17 45 and a comparatively large portion into the bar. As explained, the shearing action is away from the side of the nut blank being directly formed and the swaging effect upon the nut blank is less than would be produced 50 by a severance thereof from the bar by a swaging action only. In conjunction with our improved apparatus for producing this shearing action, we find it extremely desirable to provide both a means for clamping 55 the nut blank against tilting or twisting and a means for clamping the bar against tilting or twisting. The first of these means, namely, the means for clamping the nut blank against twisting, is shown in two 60 forms by Figs. 6, 7 and 8. In Fig. 6 there

is shown a stop and holding member for the blank formed integrally with the die members 47 as at 48. They form a receiving pocket 49 of a form to insure the proper formation of the nut blank by the angularly 70 approaching cutters. It will be apparent by reference to Fig. 8 that this pocket formation is continued rearwardly through the dies as at 50. The form of holding members is somewhat varied in the structure 75 shown in Fig. 7 and in this structure the die members are shown at 47 and are provided with a stop member preferably of an integral form as at 51. This stop member is formed to coincide with two sides of the 80 hexagonal blank and is cut away as at 52 to permit the access to the blank of clamping members 53 and 54. By reference to Fig. 5, it will be seen that these clamping members 53 and 54 are carried by elements 55 and 56 85 which are slidably adjustable by means of bolts 57 and 58 upon formations 59 and 60 which are respectively under the control of yoke members 61 and 62 embracing cams 63 and 64 upon the cam shaft 10. These cams 90 are designed to operate simultaneously to bring the clamping elements 54 and 53 together to clamp the nut blank and they are timed so as to insure clamping of the nut blank during the operation of the swaging 95 elements. This clamping of the nut blank prevents twisting of the nut under the stresses which necessarily result by the swaging and cutting action and thereby assist the shearing action of the cutters in preventing a pulling down of the corners of the nut blank. The various clamping stages are also shown in Figs. 14 to 18 inclusive.

100 The bar which is being operated upon and from which the nut blank is being formed, 105 is desirably clamped against a twisting action by a positive clamping element 65 having an adjustable foot 66 adjustable by means of bolts 67 and 68 and operable under the control of a cam 69 fitting within a cam 110 receiving pocket 70 of said element 65. Under normal conditions, the clamping member 65 is desirably operative for substantially $\frac{1}{2}$ of the entire operation of forming 115 the nut and only during the period of freedom from this clamping action may the operator force the bar inwardly to place it in position for the formation of a new nut blank. The clamp is substantially positive 120 in its action to maintain the bar against twisting or tilting, but is not sufficient to prevent a slight longitudinal rearward movement of the bar. This longitudinal movement is desirable to render the shearing action of the swaging elements more readily effective. It will be seen from the description of this clamping element, that it serves 125 not only as a clamp for preventing tilting or twisting of the bar and thereby preventing distortion of the end of the bar; but 130

- it serves as a timer whereby the operator of the machine is absolutely precluded from forcing the bar into the machine at an inopportune moment.
5. It will be noted by reference to Figs. 1, 3, 4 and 5, that each element which is reciprocable by the operation of cams upon the cam shaft 10 is assured of return to normal position by a spring element and 10 these spring elements are designated by the same numerals with subordinating letters, as 17^a, 24^a, 61^a, 62^a, and 65^a and the direction of operation of these springs is shown by the small arrows in the figures.
15. It will also be noted by reference particularly to Fig. 5, that we have provided dislodging means for the finished nut blank and the slug after the blank has been operated upon by the piercer structure shown, 20 but not described, and not forming a portion of this application. It will be sufficient to mention that the center of the nut blank is displaced by a piercer structure producing a slug which sometimes adheres 25 to one of the piercers. The finished nut blank is also ejected from the die shown in Figs. 6 and 7 and both the blank and slug are positively dislodged by the dislodging fingers 71 and 72 forming a portion of the 30 member 73 carried at the lower end of the yoke member 74. This yoke member is provided with a pocket 75 similar to those carried by the yokes previously described and operates in conjunction with a cam 76 35 to give the desired motion. As is the case with the remaining yokes, this yoke member 74 is also provided with a spring 74^a which acts in the direction indicated by the arrow in Fig. 5 and which insures a return of the yoke to non-disengaging 40 position.
- What we claim, is—
1. A machine for forming nut blanks comprising means for separating the blank from the bulk metal by a swaging action, a 45 gage for initially positioning the body metal and against which the blank rests, and means for obviating crowding of the bulk metal into the blank during the swaging 50 action.
2. A machine for forming nut blanks comprising means for separating the blank from the bulk metal by a swaging action, means for maintaining the blank stationary 55 during such action, and means for obviating crowding of the bulk metal into the blank during such action.
3. A machine for forming nut blanks comprising means for separating the blank from the bulk metal by a swaging action, means for maintaining the blank immovable longitudinally of the bulk metal during such action, and means for obviating 60 crowding of the bulk metal into the blank 65 during such action.
4. A machine for forming nut blanks comprising means for separating the blank from the bulk metal by a swaging action, a stationary gage for initially positioning the bulk metal, and means for obviating crowding of the bulk metal into the blank during the swaging action. 70
5. A machine for forming nut blanks comprising means for separating the blank from the bulk metal by a swaging action, 75 and means for holding said bulk metal against twisting, said means permitting longitudinal movement of the bulk metal.
6. A machine for forming nut blanks comprising means for separating the blank from the bulk metal by a swaging action, 80 and a clamping element intermittently effective to grip the bulk metal to hold the same against tilting, said clamping element being also effective to permit a longitudinal 85 movement of the bulk metal.
7. A machine for forming nut blanks comprising means for separating the blank from the bulk metal by a swaging action, a clamping element for the blank, and a 90 clamping element for the bulk metal, said clamping elements being intermittently effective to hold the blank and bulk metal respectively against tilting.
8. A machine for forming nut blanks comprising a pair of swaging elements, means for causing said elements to move toward each other in angular paths, and means for holding the bulk metal as it is fed into said machine against tilting, said 100 means permitting a longitudinal movement of said bulk metal.
9. A machine for forming nut blanks comprising swaging elements and means for causing movement of said swaging elements 105 in angular paths during their swaging actions.
10. A machine for forming nut blanks comprising a pair of swaging elements movable toward each other in a manner to 110 swage the blanks from bulk metal, and means for moving said elements in angular paths with their points still alining.
11. A machine for forming nut blanks comprising a pair of swaging elements, 115 means for moving said elements toward each other to swage the blank from the bulk metal, and means for guiding said elements in angular paths of alining approach. 120
12. A machine for forming nut blanks comprising a pair of swaging elements, a support for each swaging element, and means for simultaneously reciprocating said supports in angular paths to move said 125 elements toward each other.
13. A machine for forming nut blanks comprising a pair of swaging elements, a support for each swaging element, means for simultaneously reciprocating said sup- 130

ports to move said elements toward each other, and means for causing said elements to have angular approach toward each other.

5 14. A machine for forming nut blanks comprising a pair of swaging elements, a support for each swaging element, means for simultaneously reciprocating said supports to move said elements toward each other, and guide ribs and grooves for causing said swaging elements to approach each other at an angle.

15 15. A machine for forming nut blanks comprising a pair of swaging elements, a support for each swaging element, means for simultaneously reciprocating said supports to move said elements toward each other, guide ribs and grooves for causing said swaging elements to approach each other at an angle, and means for adjusting the fit of said ribs and grooves.

25 16. A machine for forming nut blanks comprising a pair of swaging elements, a support for each element, said elements supported one upon the other, means for relatively reciprocating said supports to cause said elements to approach and recede from each other, and means for causing said supports to move at an angle.

30 17. A machine for forming nut blanks comprising a pair of swaging elements, a support for each element, said elements supported one upon the other, means for relatively reciprocating said supports to cause said elements to approach and recede from each other, a rib on one of said supporting elements of angular inclination, said rib working in a groove upon the machine framework to guide said supports angularly 40 during approach of said swaging elements.

45 18. A machine for forming nut blanks comprising a pair of swaging elements, a support for each element, said elements supported one upon the other, means for relatively reciprocating said supports to cause said elements to approach and recede from each other, a rib on one of said supporting elements of angular inclination, said rib working in a groove upon the machine framework to guide said supports angularly 50 during approach of said swaging elements, and means for regulating the fit of said rib and groove.

55 19. A machine for forming nut blanks comprising a pair of swaging elements, a support for each element, said elements supported one upon the other, means for relatively reciprocating said supports to cause said elements to approach and recede from each other, a rib on one of said supporting elements of angular inclination, said rib working in a groove upon the machine framework to guide said supports angularly 60 during approach of said swaging elements, and means for regulating the fit of said rib and groove.

65 20. A machine for forming nut blanks comprising means for segregating the blanks from bulk stock, and means independent of each other for clamping the blank and stock.

70 21. A machine for forming nut blanks comprising means for segregating the blanks from bulk stock, and intermittently 75 operable for clamping the blank and stock.

75 22. A machine for forming nut blanks comprising means for segregating the blank from bulk stock, and means for intermittently clamping the stock.

80 23. A machine for forming nut blanks comprising means for segregating and forming the blank from bulk stock, and clamping means for said stock, said clamping means being automatically rendered ineffective at the end of each segregating and forming operation.

85 24. A machine for forming nut blanks comprising means for cutting said blanks from stock by an angular cutting action, 90 and means for loosely clamping said stock during said cutting action.

95 25. A machine for forming nut blanks comprising means for cutting said blanks from stock by an angular cutting action, 95 and means for clamping said blanks and stock during the cutting action.

100 26. A machine for forming nut blanks comprising a pair of swaging elements movable toward each other, a gage for initially positioning the body metal and against which the blank is adapted to rest, and means for moving said elements toward each other in a manner to hold the blank metal immovable longitudinally and to 105 avoid crowding of a surplus bulk metal into the blank during the swaging action.

In testimony whereof we affix our signatures in presence of two witnesses.

CHARLES S. LANMAN.

WILLIAM N. ESCHELMAN.
